UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,337,309.

Specification of Letters Patent. Patented Apr. 20, 1920.

Application filed February 26, 1916. Serial No. 80,690.

To all whom it may concern:

Be it known that I, CHARLES L. GOODRUM, a citizen of the United States, residing at New York, in the county of New York and 5 State of New York, have invented certain new and useful Improvements in Telephone Systems, of which the following is a full, clear, concise, and exact description.

This invention relates to telephone systems in which connections from calling to 10 called subscribers' lines are established by means of automatic or electrically operated switching devices.

The principal feature of this invention resides 15 in the provision of means whereby a plurality of brush sets, which are provided as terminals of the same telephone circuit and are carried on the same movable switch element, are employed in simultaneously 20 hunting for a desired line.

A further feature of the invention resides 25 in the provision of means whereby the brush set which first engages the terminal to a desired line will be definitely associated with the telephone circuit of which it is a terminal, and the remaining brushes will be maintained disconnected from said telephone 30 circuit.

The present invention may be employed 35 to decrease the time necessary to find and make connection to desired lines, or in certain instances may be employed to increase the size of line groups. It may be used with switches arranged either to find and make 40 connection to calling subscribers' lines, or to find and make connection to idle trunk lines. In the present disclosure the invention is shown as applied to a line finder switch, and to a trunk selecting switch.

Referring to the drawings, Figures 1 and 45 2 with Fig. 1 at the left diagrammatically indicate the apparatus and circuits employed in the present embodiment of the invention. The switch herein disclosed may be of the character of that shown in patent to Oscar F. Forsberg, No. 1,252,420, issued January 8, 1918, although obviously any switch which has a set of movable brushes may be employed. In the switch of the Forsberg 50 application above referred to ten brush sets are shown, the several sets being spirally arranged about the shaft. A separate group of terminals is provided for each brush set, and the appropriate brush is brought into

operative engagement with its particular 55 series of contacts by rotating the supporting shaft.

As a series of ten contacts is provided for each of the brushes, the switch will have a capacity of 100 lines. In the present disclosure the number of brushes may be doubled, or the number of rotary positions may be made one half the number of the Forsberg switch. Whichever structure is employed, the sets of brushes will be arranged in pairs as 2-2', 3-3', etc. The sets of brushes of each pair are arranged in alinement, but the several pairs of sets are spirally arranged about the shaft. In case it is desired to employ the present invention 70 to decrease the length of the hunting operation, but five contacts would be arranged in the series provided for each of the brush sets, and, if the number of rotary positions of the switch are decreased, it would result 75 in doubling the size of the line groups. In the first instance only five vertical steps of the switch would be required in finding the last line of a group, whereas in the second assumption, while the number of steps, that 80 is ten, for finding the last line would be the same, the size of the group would be doubled.

In the present disclosure the desired sets of brushes will also be brought into operative relation with their respective groups of 85 terminals by rotary movement of the shaft 1. This rotary movement will be accomplished by means of the stepping magnet 5, to the armature 6 of which, is secured the stepping pawl 7. The pawl 7 is arranged 90 to operatively engage the ratchet wheel 8 fixed to the rotatable shaft 9. The spur gear 10 is also fixed to the shaft 9, and when the brush shaft 1 is in its lowermost position, gear 10 operatively engages the 95 gear 11 fixed to shaft 1 near the lower end thereof. The coil spring 12 has its inner end secured to the shaft 9, and its outer end secured to the framework in any desired manner. Retrograde movement of the shaft 100 9 is prevented by means of the pawl 13, which projects from the yoke 14 pivotally supported on the pin 15. Thus it will be seen that the step-by-step rotary movement 105 of the ratchet wheel 8 will be communicated to the shaft 1 so that a different pair of brush sets 2-2', 3-3', etc., will be brought into operative relation to their respective

contact groups upon each energization of the magnet 5.

The vertical movement of the shaft 1 is caused by the magnet 16, the armature 17 of which is provided with a pawl 18, which is arranged to coöperate with the circular ratchet teeth 19 on the shaft 1 to move the brushes from set to set of contacts upon successive energizations of the magnet 16.

10 Downward movement of the shaft 1 is prevented by means of the pawl 20, which is carried by the yoke 21 pivotally mounted on the pin 15.

At the lower end of the shaft 1 is a spring 15 detent 22, which, upon the first upward step of the shaft 1, is released and operatively engages the gear wheel 10. The release and return to normal of the switch is controlled by the magnet 23, the armature 20 24 of which is fixed to the yoke 14, which carries the pawl 13. The yoke 14 is provided with a finger 25, so positioned adjacent to the finger 26 of the yoke 21 that, upon the attraction of the armature 24, the pawl 23 20, as well as the pawl 13, is retracted. The reverse rotary movement of the shaft 1 at this time is prevented, however, by means of the detent 22, and the shaft 1 is maintained in a definite rotary position by the engagement of the brushes with the contacts. As the shaft 1 approaches its normal position, the gear 11 drops into mesh with the gear 10. At the same time the detent 22 is retracted, and the switch is rotated to its normal 35 mal position by means of the spring 12.

It is to be understood that the invention is not limited to employment with a switch of the type herein disclosed, as any other two movement switch, or in fact any other 40 switch which is provided with progressively movable brushes, may be employed with the present invention.

The circuit changing device or side switch herein disclosed may be similar in character 45 to that shown in the patent to Keith and Erickson No. 815,176 of March 13, 1906. The switch shown in this patent, however, will not operate in a manner necessary to fulfil the requirements of the present invention. A circuit controlling switch, such as employed herein, is shown in the above noted application to Oscar F. Forsberg. This side switch may be caused to move its wipers either upon the energization or upon 50 the deenergization of its controlling magnet. This is accomplished by the omission from its escape wheel of the appropriate ratchet teeth.

At the left in Fig. 1 are shown two subscribers' lines, A and A', which terminate in contacts of the groups arranged to be traversed by correspondingly positioned brushes 2 and 2' on the switch shaft 1. It will be noted that the brushes 2 will traverse 60 the group of contacts in which the line A

terminates at the same time that the brushes 2' are passing over the contacts of the group in which the line A' terminates. It will be further noted that only one connecting circuit or trunk is provided for the sets of brushes 2 and 2', the set of brushes which is operatively connected to said trunk being determined by the energized or deenergized condition of the auxiliary test relay 27. The brushes 2 are normally connected to the trunk, but upon the energization of the relay 27 the brushes 2 are cut off and the brushes 2' are connected to the trunk instead. It is to be understood that a plurality or group of line finder switches will be employed in the present invention in a manner similar to that disclosed in applicant's application, Serial No. 35,326, filed June 21, 1915.

It is believed that the invention will now 85 be readily understood from a description of the manner in which the switches operate in establishing a connection.

Assuming now that the subscriber having the line A' initiates a call by removing 90 his receiver from its hook; this will complete a circuit from battery through the left winding of line relay 28, back contact and left armature of cut off relay 29 over the lower side of the subscriber's line A', 95 through the substation thereof, over the upper side of the line A', through the right armature and back contact of relay 29 and the right winding of relay 28 back to battery. Relay 28 attracts its armatures and 100 puts potential on the right terminal of the set in which line A' terminates, from the source of current 30, through test relay 31, right contact and armature of relay 28. It also completes a circuit from battery 105 through relay 32, back contact and left armature of relay 33, left armature and contact of relay 31, left contact and armature of relay 28 and the right winding of relay 28 to ground. Relay 32 is energized and locks 110 up through its left armature and contact. At its right armature it completes a circuit from battery, through the rotary stepping magnet 5, its individual interrupter contact 34, side switch wiper 35, relay 33, innermost right armature and front contact of relay 32 to ground, through the right armature and contact of relay 31. Due to the action of the individual interrupter 34, magnet 5 is repeatedly energized and deenergized, thus stepping the sets of brushes 2-2', 115 3-3', etc., successively into operative relation to their rows of contacts, until the brush 36 carried at the top of the shaft 1 engages the contact 37 individual to the group 120 of the calling line. A circuit will now be completed from battery through the escape magnet 38, side switch wiper 39, brush 36, contact 37, outermost right armature and contact of relay 32 and the right armature 125 130

and contact of relay 31 to ground. Escape magnet 38 will be energized and will move the side switch wipers to position 2.

In position 2 a circuit is completed from 5 battery through the vertical stepping magnet 16, its individual interrupter contact 40, side switch wiper 35, relay 33, innermost right armature and front contact of relay 32, and right armature and contact of relay 10 31 to ground. Due to the action of the individual interrupter 40, magnet 16 will be repeatedly energized and deenergized, thus stepping the sets of brushes 2 and 2' from set to set in their respective series of contacts. When the brushes 2' engage the contacts of the line A', a circuit will be completed from source of current 30, through test relay 31, contact and right armature of line relay 28, right contact and right brush 20 2', through condenser 41, side switch wiper 42, auxiliary test relay 27 to battery and ground. This will cause an impulse of current to pass through relays 31 and 27, and both will attract their armatures. During the 25 vertical stepping operation a circuit extended through escape magnet 38 and side switch wiper 39 in parallel with the vertical magnet 16 and wiper 35. Now, upon the attraction of the armature of relay 31, the 30 circuit for magnets 16 and 38 will be interrupted, stopping the vertical stepping action and causing the deenergization of the escape magnet 38, which, upon the retraction of its armature, moves the side switch 35 wipers to position 3. When the side switch goes to position 3, relay 27 is locked up by a circuit through its upper armature and contact and side switch wiper 42, which locking circuit will be maintained until the 40 side switch is restored to its normal position upon restoration of the switch.

Had the subscriber of line A initiated the call instead of the subscriber of line A', the operation would have been exactly the same 45 as just described, with the exception that the test circuit would have extended from the source of current 30, through relay 31, contact and right armature of the line relay 28' of line A to the right contact and the 50 right brush 2, through the innermost lower armature and back contact of relay 27, wiper 43, condenser 44, resistance 45 to battery and ground. Relay 31 would have been energized and accomplished the same functions as previously described. As the side switch would move to position 3 immediately after the test, the energizing circuit for the relay 27 would be open, thus insuring that the lower armatures of this relay 55 would remain retracted and thus maintain the brushes of the set 2 connected to the trunk.

As the side switch moves to position 3, the 60 starter wire 46 is extended through the back contact and innermost right armature of re-

lay 32, the winding of relay 33 and the side switch wiper 35 to the starter wire extension 46', leading to the next switch in the group. A circuit will now extend from battery, through the resistance 45, wiper 47, lower- 70 most armature and front contact of relay 27, left brush of the set 2' and the winding of the cutoff relay 29, to ground. Relay 29 will be energized, thus interrupting the circuit of line relay 28, which, in retracting its armatures, will return the common mechanism to its normal position. 75

In position 3 of the side switch, the side switch wipers 43 and 47 also extend the calling line through to the selector switch 80 shown in Fig. 2.

The calling subscriber may now operate his dial to send a series of impulses to the selector switch shown in Fig. 2. This switch may be of the same structure as 85 that indicated in Fig. 1. When side switch wiper 43 reached its third position a circuit was completed from battery through the right winding of trunk relay 48, side switch wiper 49, the left winding of relay 48, wiper 90 43, innermost lower armature and front contact of relay 27, right brush 2', the line terminal engaged thereby, front contact and right armature of cutoff relay 29 over the upper side of the subscriber's line A', 95 through the substation thereof, back over the lower side of the subscriber's line, through the left armature and front contact of relay 29, and through the winding of relay 29 to ground. This circuit causes 100 the energization of relay 48, which in attracting its armature completes a circuit from battery, through the winding of relay 50, front contact and armature of relay 48, back contact and armature of relay 51, back 105 contact and armature of release magnet 52 to ground. The subscriber now sends the selecting series of impulses to operate the switch shown in Fig. 2. The sending device 110 may be of any desired and well-known construction which operates to produce a series of interruptions in the line circuit. With each interruption at the sending device, the circuit of relay 48 will be broken and it will retract its armature, completing a circuit 115 from battery, through the rotary stepping magnet 53, side switch wiper 54, and also from battery through the escape magnet relay 55 in parallel with magnet 53, and thence through the front contact and innermost armature of relay 50, back contact and armature of relay 48, back contact and armature of relay 51 to ground, through the back contact and armature of release magnet 52. Relay 55, in attracting its armature, 120 will cause the energization of the escape magnet 56. As relays 50 and 55 are made slow to release, they will remain energized throughout the series of impulses. 125 Due to the successive energization and de- 130

energization of relay 48, the rotary stepping magnet 53 will be repeatedly operated to step the switch shaft 57 of the selector switch around until the sets of brushes 58 and 58' are positioned below their respective series of contacts. Upon the termination of the series of impulses, relay 55 will retract its armature, thus causing the de-energization of escape magnet 56, which, in 10 retracting its armature moves the side switch to position 2. It is to be understood that the sets of brushes 58 and 58' of the selector switch are in every way similar to the sets of brushes 2 and 2' at the finder switch shown in Fig. 1.

In position 2 a circuit is completed from battery through the vertical stepping magnet 59, its individual interrupter 60, wiper 61, front contact and armature of relay 48, 20 back contact and armature of relay 51 and back contact and armature of release magnet 52 to ground. It is to be understood that the test contact of idle trunks, that is, the right or under contact in Fig. 2, will be connected to ground through a resistance in any well-known manner. This ground connection may for example be made through a back contact of the first slow relay corresponding to relay 50. As this relay holds its 30 armatures continuously attracted whenever its switch is in use, the ground is present on the test contact only when the switch is idle. We will first assume that the brushes 58 are first to engage the contacts of an idle 35 trunk. When this occurs, a circuit will be completed from battery, through the auxiliary test relay 62, the normal lower contacts of this relay, the right brush of the set 58 and the contact engaged thereby to 40 ground through resistance 63. Relay 62, in attracting its lower armature, will complete a locking circuit for itself, which extends to ground through the front contact and outermost armature of relay 50. In attracting its 45 innermost upper armature, it completes a circuit from battery through the test relay 51, innermost upper armature and front contact of relay 62, right brush of the set 58 and the terminal engaged thereby, to ground 50 through resistance 63. Relay 51 in attracting its armature, will complete a circuit from battery through the escape magnet 56, front contact and armature of relay 51 and the back contact and armature of release 55 magnet 52 to ground. Magnet 56 will be energized and move the side switch wipers to position 3.

At the time test relay 51 is energized the line relay and consequently the first slow 60 relay at the second selector switch will also be energized which will operate to remove the ground from the test contact engaged by the right brush of the set 58, thus causing the immediate retraction of the armature of 65 relay 51. As the relay 50 is slow to release,

it will not drop off its armature during the momentary interruption of its circuit at the back contact of relay 51.

Had it happened that the calling line terminated in the series of contacts traversed by the set of brushes 58', the operation would have been the same as just described with the exception that the operation of the test relay 51 would not have been preceded by the operation of the auxiliary test relay 62. In the case now assumed, the operating circuit for the relay 51 would extend from battery through said relay 51, the innermost upper armature and back contact of relay 62, the right brush 58' and the contact engaged thereby, to ground through the resistance 63'. Thus it will be seen that, irrespective of which brush first engages an idle trunk, the switch will be stopped with said brush on the contacts of said trunk and the set of brushes on the idle trunk will be connected to the trunk circuit, the other set of brushes being maintained disconnected from the trunk circuit.

As the side switch of the selector moves to position 3, the circuit extending through the right winding of relay 48 will be interrupted, but as battery will be supplied at this time from the next selector switch to the contact engaged by the left brush 58 or 58', depending upon which has first found the idle trunk, this relay will not retract its armature, as a circuit will now exist from battery through the left brush of the operative set to the uppermost armature of relay 62, wiper 49, left winding of relay 48, wiper 43, innermost lower armature and front contact of relay 27, the right brush of the set 2' and the contact engaged, the front contact and right armature of relay 29, the upper side of the subscriber's line A' through the substation thereof, back over the lower side of the line A' through the left armature and front contact of relay 29, to ground through the winding of relay 29.

The release of the line finder and the first selector switches at the termination of the conversation is controlled at the back contact and outermost armature of relay 50. When the calling subscriber replaces his receiver upon the hook, the above traced circuit through the left winding of relay 48 is interrupted and it retracts its armature, thus permanently opening the circuit for the relay 50 which in turn becomes de-energized and completes a circuit from battery through the release magnet 23 of the line finder switch, back contact and right armature of relay 33 and from battery through the release magnet 52 and off-normal contact 64 125 and thence to ground through the back contact and outermost armature of relay 50. The release magnet 23 thereupon locks up through a circuit including off-normal contact 65 and the contact 66, and remains 130

locked until contact 65 is opened as the switch reaches its normal position. Release magnet 52 also locks up through off-normal contact 64 and its armature and front contact, thus insuring the full return to normal of the selector switch.

It will thus be seen that the arrangement herein disclosed provides means whereby two sets of brushes may each hunt over their respective series of contacts at the same time and whereby the brush set, which first engages the contacts of the desired line, will be maintained in engagement with said contacts and will also be connected to the trunk circuit, the other set of brushes being maintained disconnected from the trunk circuit. While the invention herein disclosed is applied to a two-wire multiple system, it is obvious that it is equally applicable to systems of other characters and that other means than those disclosed herein may be employed for determining which of the brush sets will be connected to the trunk circuit.

What is claimed is:

- 25 1. In a telephone system, a switch including a plurality of brushes, series of circuit terminal contacts, one for each of said brushes, each series being the terminals of a different group of circuits, automatic means for simultaneously moving said brushes over said series of contacts, and a single test relay for stopping the movement of said switch when any one of said brushes engages the contact of a desired circuit.
- 30 2. In a telephone system, a switch including a plurality of brushes, series of circuit terminal contacts, one for each of said brushes, said series being the terminals of different groups, automatic means for simultaneously moving said brushes over said series of contacts, a test relay, a circuit for said relay having branches including said brushes, respectively and means for closing said circuit when any one of said brushes engages a desired circuit terminal.
- 35 3. In a telephone system, a switch including a plurality of sets of brushes, series of circuit terminal contacts, one for each of said sets of brushes, a telephone circuit, a single relay for joining said circuit to one or another of said brush sets, automatic means for simultaneously moving said brush sets over their series of contacts, and means operated when one or the other of said brush sets engages the contacts of a desired circuit for stopping the movement of said switch and joining the engaged brushes to said telephone circuit.
- 40 4. In a telephone system, a switch including a pair of brushes, a telephone circuit, a relay for connecting one or the other of said brushes to said circuit, a series of line terminal contacts, one for each of said brushes, automatic means for simultaneously moving said brushes over said series of contacts, and

means controlling the operation of said relay whereby the brush which first engages the contact of a desired line will be connected to said telephone circuit.

5. In a telephone system, an electrically operated switch including two brushes, series of telephone line terminal contacts, one for each of said brushes, a telephone circuit, a relay for joining one or the other of said brushes to said circuit, automatic means for simultaneously moving said brushes over said series of contacts, a test relay and a circuit for said test relay having branches extending through said brushes, respectively, said first-named relay being included in one of said branches.

6. In a telephone system, a switch including a plurality of brushes, series of contacts, one for each of said brushes, groups of telephone lines terminating in said series of contacts respectively, means operating on the initiation of a call on one of said lines for automatically and simultaneously moving said brushes over said series of contacts, and a single test relay for stopping the movement of said switch when any one of said brushes engages the contact of a calling line.

7. In a telephone system, a switch including a plurality of brushes, series of contacts, one for each of said brushes, telephone lines terminating in said contacts respectively, means actuated upon the initiation of a call on one of said lines for automatically and simultaneously moving said brushes over said contacts, a test relay for stopping the movement of said switch, a circuit for said relay having branches including said brushes respectively and the contacts of said series and means for closing said circuit when any one of said brushes engages a desired line terminal.

8. In a telephone system, a switch including a pair of brushes, series of contacts, one for each of said brushes, telephone lines terminating in said contacts respectively, a telephone circuit, a relay for connecting one or the other of said brushes to said circuit, means responsive to the initiation of a call on one of said lines for automatically and simultaneously moving said brushes over said series of contacts, and means controlling the operation of said relay whereby when one or the other of said brushes engages the contact of said calling line, said brush will be connected to said telephone circuit.

9. In a telephone system, a switch having a plurality of brushes, series of contacts one for each of said brushes, each series being the terminals of a different group of trunks, trunk circuits terminating in said contacts respectively, automatic means for simultaneously moving said brushes over said contacts, and a single test relay for stopping the movement of said switch when any one

of said brushes engages the contact of an idle trunk.

10. In a telephone system, a switch having a plurality of brushes, series of contacts one for each of said brushes, trunk lines terminating in said contacts respectively, automatic means for simultaneously moving said brushes over said contacts, a test relay for stopping the movement of said switch, 10 a circuit for said relay, and means for completing said circuit through any one of said brushes and the contact of the first encountered idle trunk.

11. In a telephone system, a switch having a pair of brushes, series of contacts one for each of said brushes, trunk lines terminating in said contacts respectively, a telephone circuit, a relay for connecting one or the other of said brushes to said circuit, 15 automatic means for simultaneously moving said brushes over said contacts, and means controlling the operation of said relay whereby when one or the other of said

brushes engages the contact of an idle trunk, said brush will be connected to said telephone circuit. 25

12. In a telephone system, an electrically operated switch having two brushes, series of contacts one for each of said brushes, trunk lines terminating in said contacts respectively, automatic means for simultaneously moving said brushes over said contacts, a telephone circuit, a test relay for stopping the movement of said switch, a circuit for said relay having alternative 30 branches extending through said brushes respectively, and a second relay, said second relay being operative to control the extension of said test circuit to the brush which first engages the contact of an idle trunk 35 and to operatively associate said brush with said telephone circuit.

In witness whereof, I hereunto subscribe my name this 25th day of February A. D., 1916.

CHARLES L. GOODRUM.
